UNITED STATES PATENT OFFICE.

OTTO GAMPER, OF ZURICH, SWITZERLAND.

MACHINE FOR FACILITATING THE PACKING OF MAGNETIC OBJECTS OF OBLONG SHAPE.

1,080,435.

Specification of Letters Patent.

Patented Dec. 2, 1913.

Application filed December 3, 1912. Serial No. 734,792.

To all whom it may concern:

Be it known that I, OTTO GAMPER, a citizen of the Republic of Switzerland, residing at Zurich, Switzerland, have invented new 5 and useful Improvements in Machines for Facilitating the Packing of Magnetic Objects of Oblong Shape; and I do hereby declare the following to be a full, clear, and exact description of the invention, such as 10 will enable others skilled in the art to which it appertains to make and use the same, reference being had to the accompanying drawings, and to letters or figures of reference marked thereon, which form a part of this 15 specification.

In my Patent 1,014,869 of January 16th, 1912, I have described a machine for facilitating the packing of magnetic objects of oblong shape, in which machine magnets are 20 arranged at a distance corresponding to the length of the objects, which magnets have their opposite poles directed toward each other. The magnets form a groove between them and a feeding device causes the objects 25 to pass between the magnet poles and while the objects are being placed parallel by the magnetic attraction of the poles, they are moved forward by the carrier. The objects placed parallel in this manner during the 30 moving may be removed by hand from the feeding device and packed in boxes. This can only easily be done when the objects are of such length that they can be seized by the whole hand. For short objects where the 35 magnetic poles are arranged at only a small distance from each other, so that one cannot get in by the whole hand but only by one or two fingers, this device is not so handy. In this case the filling of the short objects in a 40 packing receptacle would be difficult. There has also been proposed a device in which there is provided a vertical groove which is closed at four sides. In this device the direction of filling coincides of course with the 45 longitudinal direction of the groove. Because the filling opening has only a small cross-section this machine works only very slowly. The vertical groove renders a control impossible and causes obstruction. 50 By the device according to this invention these drawbacks are overcome thereby, that a horizontal stationary groove or canal is formed between unlike poles of a stationary magnet the feeding being performed at the 55 same time on the whole length of the groove

and the emptying of the groove being performed transverse to the direction of filling in a packing receptacle after the compression of the objects in the groove.

In the drawings an example of the machine forming the subject matter of this invention is shown.

Figure 1 is a side elevation of the same partly in section. Fig. 2 is a vertical section on line A—B of Fig. 1. Fig. 3 is a plan view 65 of the same. Figs. 4 and 5 are detail views.

A shaft 21 which is impelled by a motor not shown in the drawing continually rotates and therewith rotates an eccentric 16, on which there rests by means of yielding 70 plates 11 a rocking plate 14 which is arranged at the front side of a receptacle 15. The plates 11 are yieldingly mounted on oscillating bars 12 and 13 so that the whole receptacle 15 can rock therewith. Below the 75 front side of the rocking plate 14 a groove or canal is formed by two feeding plates 4 and 5 of non-magnetic material, the plate 4 being secured to the leg 1 and the plate 5 to the leg 3 of a horse-shoe magnet. The magnet is excited by a magnet coil 18. The leg 3 is movable on a support 2 by means of a screw 7, so that the distance of both legs can be adjusted. Between both legs 1 and 3 a shallow trough 6 is mounted to turn about 80 a hinge 22 and may be exchanged. A beater 19 is mounted to turn about the same hinge in the direction of the arrow (Fig. 1) and the beater is held in vertical direction by a spring 19^x. The trough 6 rests on a strong 85 spring 6^x and is held by it in horizontal position between the legs 1 and 3 of the horse-shoe magnet. A foot lever 8 operates firstly a switch 9 inserted in the circuit of the magnet coil 18, which switch is opened by moving the foot lever downward, and secondly a pusher rod 10 which is raised by moving the foot-lever downward, whereby the rocking plate is lifted from the eccentric 16, so that 90 the feeding is stopped. At the same time a plate 17 is raised, which is arranged above the feeding plate. By this means the plate 17 is moved in the path of the objects falling down from the rocking plate.

The machine operates as follows: If the 105 foot lever is in its upper position the switch 9 is cut in and the horse-shoe magnet is excited, so that there is a strong magnetic field between the legs 1 and 3. The rocking plate 14 is rocked by the eccentric 16, so 110

that nails in the receptacle 15 slide on the rocking plate and singly fall between the feeding plates 4, 5, where they move in the magnetic field so that by moving farther 5 down they move parallel into the trough 6. After the trough is filled and the groove between the feeding plates partly filled with loose parallel nails the foot lever is moved downward, the switch 9 is opened and the 10 exciting of the horse-shoe magnet is stopped and the nails in the groove will sink into the trough. At the same time the rocking plate 14 is lifted from the eccentric 16 so that the feeding is stopped and the plate 17 15 is turned in the path of the nails falling in the groove, so that they are prevented from moving farther downward. Then the beater 19 is moved downward against the force of the spring in the direction of the arrow 20 (Fig. 1) and the nails are closely pressed thereby. Hereafter a packing box 20 indicated in dotted lines, Fig. 1 is moved onto the free end of the trough 6, the latter is moved downward and the nails placed parallel 25 are suddenly delivered in the packing box which is wholly moved on the trough. After the trough is emptied it moves automatically upward between the legs of the magnets and is ready for use again. In 30 this manner it is possible to place the smallest magnetic objects of oblong shape parallel and to fill them in packages.

Since the objects can be seen while they are placed parallel, the objects which would 35 cause trouble in other devices, (for example waste of wire, nails which are longer than those to be packed, and the like) can be removed by hand without stopping the feeding.

40 By a machine according to this invention there may also be separated nails of different lengths by correspondingly constructing the groove between the two legs of the magnet. For separating nails of two different 45 lengths the described machine may be used without any change, by adjusting the groove

to the length of the short nails. The long nails remain on the mouth, where they may be removed by hand.

I claim:

1. In a device for facilitating the packing of slender magnetic objects of oblong shape, a horse-shoe electro-magnet, a canal of U-shaped cross-section arranged between the legs of the electro-magnet, and feeding 55 means arranged above the open longitudinal side of said canal adapted to distribute the objects to be packed over the whole length of said canal.

2. In a device for facilitating the packing 60 of slender magnetic objects of oblong shape, a horse-shoe electro-magnet, the legs of said magnet being adjustable to different distances from each other and forming a horizontally arranged groove, a hinged bottom 65 member provided with a free end adapted to receive a packing box, and feeding means arranged above the open longitudinal side of said groove adapted to distribute simultaneously the objects to be packed over the 70 whole length of said groove.

3. In a device for facilitating the packing of slender magnetic objects of oblong shape, a horse-shoe electro-magnet forming a horizontally arranged groove, a shallow trough 75 hinged below the groove provided with a free end adapted to receive a packing box, into which the trough is emptied in the transverse direction of the feed, feeding means arranged above the open longitudinal 80 side of said groove adapted to distribute simultaneously the objects over the whole length of said groove, and a device adapted to interrupt the current exciting the magnet and stop the feeding simultaneously.

In testimony that I claim the foregoing as my invention, I have signed my name in presence of two subscribing witnesses.

OTTO GAMPER.
